P. R. GLASS

TAPE APPLYING APPARATUS

Filed Nov. 26, 1919

UNITED STATES PATENT OFFICE.

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY.

TAPE-APPLYING APPARATUS.

Application filed November 26, 1919. Serial No. 340,735.

To all whom it may concern:

Be it known that I, PERLEY R. GLASS, a citizen of the United States, residing at Wayland, in the county of Middlesex and State of Massachusetts, have invented certain Improvements in Tape-Applying Apparatus, of which the following description, in connection with the accompanying drawings, is a specification, like reference characters on the drawings indicating like parts in the several figures.

My invention relates to apparatus for laying tape upon such surfaces as the uppers of shoes, where it may be used for the reinforcement of the work.

An object of the invention is to provide an improved portable organization which may readily be moved to various parts of the work, and which will effectively cause the application and adhesion of the tape thereto. In the accomplishment of this purpose, in the illustrated embodiment of the apparatus, a frame, arranged to be grasped by the operator to advance it over the surface upon which the tape is laid, carries a pressure surface with heating means therefor and means for supplying tape between the pressure surface and the work.

Another object of the invention is to arrange an improved combination of elements for the division of the tape when the end of the surface to which it is to be applied is reached. This may be accomplished by associating with the pressure surface on the frame a tape-dividing means, as a cutting member, movable into proximity with the pressure surface. Preferably, this dividing or cutting means is actuated by means arranged for engagement by the hand of the operator grasping the frame.

A further object is to effect, in a better manner, a preliminary feed of the tape in preparation for the feed which occurs during its application. As shown herein, the supplying and applying means are so arranged that the tape is fed to the work during the movement of the apparatus, and there is also co-operating, independently operable tape-feeding means, which may, similarly to the dividing means, be actuated by the hand of the operator which produces the travel of the apparatus.

Hereinafter other objects will be made

evident, reference being had to the accompanying drawing, in which—

Fig. 1 is a side elevation of a particular embodiment of the invention, parts being broken away;

Fig. 2 is a horizontal section on the line 2—2 of Fig. 1; and

Fig. 3 is a perspective view illustrating the use of the apparatus.

The frame 10 is shown as consisting of a main or body portion 12 which extends vertically in the operation of the apparatus, upper and lower arms 14 and 16, respectively, projecting horizontally from the body portion, and a handle 18 connecting the arms and lying generally parallel to the body portion. Above the portion 12 at its juncture with the arm 14 is an upwardly and rearwardly extending arm 20, at the outer end of which is fixed a horizontal spindle 22 for the support of a roll 24 of the tape which is to be applied. From the roll the tape, which is indicated by the letter T, passes over a guide roll 26 journaled at the juncture of the arms 14 and 20 and the body portion 12, and then enters a vertical passage 28 extending along the body portion near the side adjacent the handle. Emerging from the passage, the tape passes in contact with the inner edge of a yieldable pressure roll 30 mounted upon a leaf spring 32 fastened near its upper end to the outside of the body. Within the passage, the tape, which preferably bears, upon its inner side as it is wound upon the roll, an adhesive substance adapted to be softened by the application of heat is subjected to the action of a heating device, preferably in the form of an electric unit 34 contained within a vertical bore in the body portion parallel to the passage 28. The uncoated side of the tape comes in contact with the heated surface, therefore having no tendency to adhere thereto; while the opposite side, upon which the adhesive material is softened, is separated from the adjacent wall of the passage by a substantial clearance. To permit the unimpeded travel of the apparatus, the unit is connected to a source of current by flexible conductors 36, the length of which is such as to enable the operator to move it to any part of the support upon which the work is laid. Below the roll 30, the tape T

crosses a guideway 38, extending horizontally in the arm 16, which arm is of considerable cross-section and is recessed to furnish a casing for the actuating elements of the apparatus, and then over a curved pressure surface 40, which at its lower extremity may be flattened to force the tape against the work over a substantial length.

Mounted to reciprocate in the guideway 38 is a cutting blade 42 movable across the path of the tape T between the roll 30 and the pressure surface 40. To actuate the blade, its end adjacent to the handle is connected by a link 44 to an arm 46 fast upon a shaft 48 rotatable between the sides of the arm 16. Fixed to the shaft 48 beside the arm 46 is a segmental pinion 50 meshing with a rack 52 formed upon the lower extremity of a rod 54. This rod is movable within a vertical bore 56 lying axially of the handle 18 and is guided by openings in the arms 14 and 16. In a space between the rod and handle and surrounding the former is a helical spring 58 contacting with the arm 16 and with an enlarged portion at the upper end of the rod, so that it exerts its tension to hold the rod in a normally raised position, a stud 60 carried by the arm 14 and extending into a vertical slot 62 in the rod outside the handle limiting the extent of movement of said rod. The enlarged upper portion of the rod 54 is divided at 64, and has between the separated sides a curved surface 66 arranged for engagement by the thumb of the operator as he grasps the handle 18 to enable him to lower the rod and thus put into motion the parts actuated thereby. The rod also has at its upper end a head 68, to which pressure may be applied if it is desired to use a greater force than that previously indicated for depressing the rod.

Rotatable about a shaft 70 fixed in the arm 16 is a feed roll 72 co-operating and being horizontally aligned with the pressure roll 30. This roll 72 is preferably corrugated or grooved transversely to cause it to more effectively engage the tape and to give less surface for adhesion. Mounted to oscillate about the shaft 70 in proximity to the roll 72 is an arm 74 having pivoted upon it a pawl 76 operating over ratchet teeth 78 surrounding one extremity of the roll 72. This arm 74 is joined by a link 80 to an arm 82 fixed upon the shaft 48. The parts are so related that as the shaft 48 is rotated by the downward thrust of the rod 54 during the cutting of the tape T, the pawl 76 moves idly over the ratchet teeth 78. When, however, the rod rises under the influence of the spring 58, during which time the blade 42 is being withdrawn, the pawl engages the teeth and rotates the roll 72 in an anti-clockwise direction, as viewed in Fig. 1 of the drawings. This produces an

advance of the tape, drawing a sufficient amount from the roll 24 to bring its free end beneath the pressure surface 40.

In Fig. 3 my improved apparatus is illustrated as it appears in use when applying tape about a portion of the inner side of a shoe vamp V. The operator, grasping the handle 18, presses, by the horizontal portion of the surface 40, the end of the tape into contact with the beginning of the area to be covered, causing the adhesion of said tape to the work, and then draws the apparatus over the desired area, continuing the downward pressure. This simultaneously produces a feed of the tape from the roll 24 and its adhesion to the work, it being first warmed ready for application during its travel through the passage 28, over the pressure roll 30 and beneath the contact surface 40. When the end of the area to be covered is reached, the operator forces down the rod 54 by bearing with his thumb upon the surface 66, or by pressure upon the head 68, producing forward movement of the blade 42 and the severing of the tape. The travel of the apparatus is continued until the end thus made is brought into adhesive contact with the work, and then the apparatus is raised and the rod released. The spring 58, returning the rod to its normal position, causes through the intermediate connections the forward movement of the pawl 76 and the consequent rotation of the roll 72, feeding the end of the tape past the guideway 38 and beneath the pressure surface 40 in preparation for its application to another area. It will be observed that the cutting of the tape and its preliminary feed are accomplished by a single operation through actuating mechanism common to both the blade and the feed roll.

Having described my invention, what I claim as new and desire to secure by Letters Patent of the United States is:

1. In a tape-applying apparatus, a frame arranged to be grasped by the operator for movement over the work and having a pressure surface, means for heating the pressure surface, and means mounted upon the frame but separated from said frame and the source of heat and arranged to carry a supply of tape for delivery between the pressure surface and work, the condition of said tape being changed by heat after leaving the supplying means to prepare it for application.

2. In a tape-applying apparatus, a frame having a body portion and a handle, there being a pressure surface upon the body portion, and a heating device carried by the body portion and arranged to transmit heat through said body portion to the pressure surface.

3. In a tape-applying apparatus, a frame having a portion provided with a passage

and a pressure surface, means for heating said frame portion, and means mounted upon the frame for supplying tape through the passage to the pressure surface there being provision for maintaining one side of the tape out of contact with the walls of the passage.

4. In a tape-applying apparatus, a frame having a portion provided with a passage and a pressure surface, means for heating said frame portion, the passage extending substantially the entire length of the heating means and in proximity thereto, and means for supplying tape through the passage to the pressure surface.

5. In a tape-applying apparatus, a frame having a body portion provided with a curved pressure surface, substantially horizontal arms extending from the body portion near opposite extremities, a substantially vertical handle connecting the arms, and means mounted at the top of one of the arms and arranged to carry a supply of tape for delivery to the pressure surface.

6. In a tape-applying apparatus, a frame having a body portion provided with a pressure surface and a recess, arms extending from the body portion near opposite extremities, a handle connecting the arms, a heating unit contained in the recess, and means for supplying tape to the pressure surface, the parts being arranged to cause the tape to travel in contact with the body portion adjacent to the heating unit.

7. In a tape-applying apparatus, a frame having a body portion provided with a pressure surface, a recess and a passage extending along the recess, a handle for the frame, a heating unit contained in the recess, and means for supplying tape to the pressure surface.

8. In a tape-applying apparatus, a frame arranged to be grasped by the operator for movement over the work and having a pressure surface, means for heating the pressure surface, means mounted upon the frame for supplying tape between the pressure surface and work, and guide rolls for the tape near opposite extremities of the body portion and arranged to direct the tape from the supplying means in close proximity to the heating means.

9. In a movable tape-applying apparatus, tape-supplying means, heating means, tape-applying means arranged to feed tape to the work in the movement of the apparatus, and independently operable feeding means arranged to advance the tape in proximity to the heating means.

10. In a movable tape-applying apparatus, tape-supplying means, heating means, tape-applying means arranged to feed tape to the work in the movement of the apparatus, a member in contact with which the tape is thus fed, and means for moving said mem-

ber to effect an independent feed, both feeding means being arranged to advance the tape in proximity to the heating means.

11. In a tape-applying apparatus, a frame arranged to be grasped by the operator for movement over the work and having a pressure surface, means mounted upon the frame for supplying tape to the pressure surface, tape-feeding means, and actuating means for the feeding means movable longitudinally of the frame.

12. In a tape-applying apparatus, a frame having a body portion and a handle, there being a pressure surface formed upon the body portion, a rotatable roll carried by the body portion at one extremity of the pressure surface for contact with the tape, and means associated with the handle for rotating the roll to feed the tape to the pressure surface.

13. In a tape-applying apparatus, a frame arranged to be grasped by the operator for movement over the work and having a pressure surface, means mounted upon the frame for supplying tape to the pressure surface, a rotatable roll for contact with the tape, a handle carried by the frame and being substantially vertical to the surface to which the tape is to be applied, an actuating member movable upon the handle, and connections between the actuating member and roll arranged to rotate said roll.

14. In a tape-applying apparatus, a frame arranged to be grasped by the operator for movement over the work and having a pressure surface, means mounted upon the frame for supplying tape to the pressure surface, a guide roll for the tape carried by the frame, a feed roll rotatable in the frame in close proximity to the applying surface, and means arranged to rotate the feed roll.

15. In a tape-applying apparatus, tape-supplying and applying means arranged to be moved over the work in the application of the tape, means associated with the applying means for operating upon the tape, a handle by which the apparatus is manipulated, and means movable longitudinally of the handle for actuating the associated means.

16. In a tape-applying apparatus, a frame arranged to be grasped by the operator for movement over the work and having a pressure surface, means mounted upon the frame for supplying tape to the pressure surface, means intermediate the supplying means and pressure surface for operating upon the tape, a handle carried by the frame and having an axial opening, a rod movable through the opening, and operating connections between the rod and intermediate means.

17. In a tape-applying apparatus, a frame arranged to be grasped by the operator for movement over the work and having a pressure surface, means mounted upon the frame

for supplying tape to the pressure surface, means intermediate the supplying means and pressure surface for operating upon the tape, a handle carried by the frame and having
5 an opening, a rod movable through the opening and provided with a rack, a pinion meshing with the rack, and operating connections between the pinion and intermediate means.

18. In a tape-applying apparatus, a frame
10 arranged to be grasped by the operator for movement over the work and having a pressure surface, means mounted upon the frame

for supplying tape to the pressure surface, means intermediate the supplying means and pressure surface for operating upon the 15 tape, a handle carried by the frame, a rod movable through the end of the handle in the direction of its axis, a spring acting upon the rod within the handle, and operating connections between the rod and intermediate means.

In testimony whereof I have signed my name to this specification.

PERLEY R. GLASS.
